UNITED STATES PATENT OFFICE

JOHN B. FLYNN, OF DETROIT, MICHIGAN, ASSIGNOR TO TERNSTEDT MANUFACTURING COMPANY, OF DETROIT, MICHIGAN, A CORPORATION OF MICHIGAN

COACH LATCH

Application filed January 14, 1928. Serial No. 246,672.

This invention relates to coach latches, and has for its object a simple latch construction in which provision is made for continuously lubricating the sliding bolt, for the purpose 5 of making the retraction easy and preventing squeaking and creaking of the bolt.

Another feature is that the sliding bolt is so constructed that it can be used either with a remote control inside actuator or with a direct 10 inside actuator.

Fig. 1 is a view of the rear of the latch in elevation.

Fig. 2 is a section taken on the line 2—2 of Fig. 1.

Fig. 3 is a section taken on the line 3—3 of Fig. 2.

a designates the front plate; *b* the face plate. *c* is a latch frame or back plate arranged to cover the outside rollback abutment 20 *d*, and the inside rollback abutment *e*. *f* designates a rearward extension or remote control connection. This is guided through the portion *h* of the frame between the struck out lugs *i* and *j* of the front plate. *k* designates 25 the usual spring; *m* the outside rollback. The sliding bolt is provided with a bolt head *n*.

A brass fixture *p* can be secured on the back of the face plate *b* by means of screws. This has a dual function; it forms an additional 30 guide for the sliding bolt head, more reliable and certain than the thin walled opening through the face plate. Additionally it serves as a wick container. The wick is designated *o* and is saturated with lubricant. 35 This, of course, will stay in the container indefinitely and serve to keep the lock bolt lubricated. Furthermore, an oil hole can be provided through the face plate *b* for soaking the wick from time to time with additional 40 oil. This hole is designated *q*. *r* designates a boss in the back plate. This is an anti-rattler adapted to bear against a lever (not shown), which can function against the inside retrac- 45 tor abutment *e*.

45 The latch is an interchangeable remote control or direct control latch. Inasmuch as I am not claiming these several retracting elements in combination with the latch, but only a latch capable of use in connection with these 50 several elements I find it unnecessary to show

these common forms of retractors, as it will be evident to anyone skilled in the art that they may be easily applied to the latch structure that is built up to take them.

What I claim is:

1. In a coach latch, the combination of a casing, a sliding bolt and other moving parts, and a reservoir secured to the casing and adapted to slidably engage the longitudinally guided face of said bolt and containing a lubricant to lubricate some of the moving parts. 51

2. A coach latch, having in combination, a latch casing comprising, a front plate and a face plate, a sliding bolt guided to pass through the face plate and slide on the back 60 of the front plate, a lubricating reservoir 65 removably secured on the back of the face plate and containing a wick to provide lubricant to the bolt head.

3. A coach latch, having in combination a latch casing comprising, a front plate and a face plate, a sliding bolt guided to pass through the face plate and slide on the back of the front plate, a lubricating fixture removably secured to the back of the face plate and 70 slidably engaging the bolt whereby the said fixture serves both as a bolt guide and a lubricant reservoir. 75

4. A coach latch, having in combination a latch casing comprising, a front plate and a face plate, a sliding bolt guided to pass through the face plate and slide on the back of the front plate, a lubricant storage fixture secured on the back of the face plate and serving as a guide for the bolt and containing a well for continuously providing lubricant to the lock head, said face plate being provided with an oil introducing perforation leading into the said well. 85

5. A coach latch comprising, a housing, a bolt slidable therein, said housing having a face plate and a front plate, and a fixture removably secured to the back of the face plate and slidably engaging the bolt and serving to guide and continuously lubricate the said bolt as it passes through the face plate. 95

In testimony whereof I affix my signature.
JOHN B. FLYNN.
